UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,408, dated December 16, 1890.

Application filed October 28, 1890. Serial No. 369,621. Term of patent 14 years.

To all whom it may concern:

Be it known that I, GEORGE H. BABCOCK, a citizen of the United States, residing in Plainfield, in the county of Union and State of New Jersey, have invented and produced a new and original Design for Roofing or Sheathing Tiles, of which the following is a specification, reference being had to the accompanying drawings, forming a part thereof.

10 The design relates to a clay or other tile in which the ornamental effects are produced by its contour.

15 The design consists of a tile the outline of which is substantially of Gothic form and its surface of a gradually-rising curved contour, merging at or near the lower edges of the tile in a raised horn or nose.

20 In the accompanying illustrations, Figure 1 illustrates a face view of a tile of the new design; Fig. 2, a transverse vertical section of the same; Fig. 3, a cross-section taken on the line 3 3 of Fig. 1.

25 As illustrated, the tile is substantially of Gothic form, provided at its upper sides *a b* with upturned flanges, its lower side being of curved form terminating in a point. The con-

tour of the surface of the tile is substantially flat adjacent to the two upper sides *a b*, but gradually rises from all sides until it merges in a raised nose or horn *e*. The major portion 30 of the surface of the tile rises from all sides in a concave curve, which gradually increases in concavity to said nose or horn, with the exception of the lower side of the tile surface, which rises in a convex curve to the nose or 35 horn, as shown, and these two oppositely-curved surfaces merge gradually into one another.

The ornamental effect produced by this horn-surfaced tile is a marked one on account 40 of the light and shade thereon and the shadow produced by the horn.

What is claimed is—

45 The design for a tile, substantially as described and shown.

In witness whereof I have hereunto set my hand, this 2d day of October, A. D. 1890, in presence of two witnesses.

GEORGE H. BABCOCK.
